PARAFFINING MACHINE

Lydia E. Koch, New York, N. Y.

Application November 28, 1933, Serial No. 700,153

7 Claims. (Cl. 91—44)

This invention relates to improvements in paraffining machines, and more particularly for impregnating paper bottles inside and outside simultaneously with a minimum film of paraffine.

Among the principal objects which the present invention has in view are: To provide an apparatus particularly designed to coat with a paper bottle making machine which forms the subject matter of a separate application; to provide an apparatus which will take care of the paraffining of the bottle as it passes out from the paper bottle making machine and brings such bottle completely paraffined directly to a bottle filling machine; and to obtain other advantages and results as may be brought out in the following description.

In the drawings:

Fig. 1 is a longitudinal elevation of the paraffine machine and the delivery end of a paper bottle making machine showing their operative connection;

Fig. 2 is a plan view of the same;

Fig. 3 is an end elevation of the paraffining chamber partially broken away;

Fig. 4 is a longitudinal section of the paraffining chamber and the bottle carrying chain, shown as taken on line 4—4 of Figure 3;

Fig. 5 is a plan view of the bar and coating mechanism for operating the doors and the valves for controlling the flow of paraffine;

Fig. 6 is a side elevation of Fig. 5 showing the parts in their inoperative position;

Fig. 7 is a similar view to Fig. 6 showing the parts in their operative position;

Fig. 8 is a plan view from the bottom of the cam for controlling the movement of the doors shown in dotted lines Fig. 5.

Fig. 9 is a cross section through the cam showing the position of the cam-follower in the inoperative position;

Fig. 10 is a view similar to Fig. 9 showing the cam-follower in the operative position;

Fig. 11 is a sectional detail of the atomizer nozzle.

As seen in the drawings, the reference numeral 15 is the main driving pulley of the paper bottle making machine, 16 the delivery end only of which is shown. 17 is the connecting bar to the rack gear which is pivoted at 18 as shown in Fig. 2. 19 is a link bar pivoted at 20 on the connecting bar 17 and is attached at the opposite end by a pivot 21 to a bar 22 for controlling the doors and paraffine supply.

I have not shown the rack gear as it forms no part of this invention. I may say, however, that this rack gear is utilized in the paper bottle machine forming the subject matter of a separate application, controlling the movement of the winder, turrets and cooperating mechanism.

The numeral 23 is the frame of the paraffine machine having an extension bracket 24. 25 is a heating chamber which is supported on a supplemental frame 26 upon which is contained a heating element 27. The chamber is a three-sided chamber with open ends, and is designed for a purpose which will hereinafter appear. 28 is the pump chamber which is supported on the frame 23 and is preferably rectangular in cross section. 29 is the paraffine pump which is shown in the broken away portion of the chamber being driven by spindle 30 connected to electric motor 31 supported on the frame 23 as indicated. 32 is the paraffining chamber which is provided with a cover 33 which may be removed to disclose the interior of the chamber for inspection purposes. The chamber 32 is supported on top of the pump chamber 28 and is provided with laterally extending chambers 34, one at each side as indicated in Fig. 3. 35 are a pair of doors located in suitable guideways 36 and 37 at the top and bottom respectively. 38 are a similar pair of doors located in suitable guideways 39 and 40. The doors 35 are located at the entrance end of the bottles to be paraffined and the doors 38 at the exit end.

In order to carry the bottles to and through the chamber 32, I have provided the endless carrier chain arranged in pairs 41, 41 and carried at the end by sprocket wheels 42, 42 suitably journaled in bearings in the paper bottle making machine as indicated in Fig. 1. The chains 41, 41, pass over sprocket wheels 43, 43 journaled in suitable bearings 44 in the bracket 45 secured to the frame 23 at the opposite end, and also over the guiding sprockets 47 and 48 and journaled in the frame 23 beneath the pump chamber 28.

The carriers 41, 41, carry suitably attached to the links thereof, the bottle supporting rings 49 which are located at equal distance apart as indicated in Fig. 2.

The carrier chains 41, 41 with the supporting rings 49 pass through orifices 50 and 51 in the doors 35 and 38 respectively when such doors are closed.

In order to provide for the supply of paraffine in a liquid state to the chamber 32, I provide the supply pipe 52 as indicated in full lines in Fig. 4 and in dotted lines in Fig. 3. The pipe 52 is provided with branch pipes 53, 53, one at each side which extend up into the lateral chambers and incline downwardly through them near the top into the casings 54 having an end opening 55 opposite the ends of atomizer nozzle 56 which preferably are of the type shown in Fig. 11. The casings 54 are provided with bottom orifices 57 designed to carry the surplus drip from the atomizer casing 54 down through the chamber 32 into the chamber 28 when the valves are closed.

5 The supply pipe 52 also has a central atomizer nozzle 58. The side atomizer nozzles are designed to impart a fine mist on the exterior of the bottle and thoroughly permeate the paper, and the central atomizer 58 is designed to likewise impart a similar misty film of paraffine to the interior of the bottle, which is upside down.

10 59 is a spindle journalled in the brackets 60 and is secured on the frame 23. The spindle 59 carries a ratchet wheel 61 which is engaged by a pawl 62 as shown in Figs. 1 and 2. The pawl 62 is carried on the end of bar 63. 64 is a gear pinion secured on the spindle 59 and meshing with a gear pinion 65 carried on the spindle 66 journalled in the bracket 60. 67, 67 are sprocket wheels secured on the spindle 66 and carrying the endless sprocket chains 68, 68, which are provided with bottle supporting rings 69 at equal distance apart. The endless sprocket chain 68, 20 68 extends over sprocket wheels 70, 70, at the opposite end. The sprocket wheels 70, 70 are secured on the spindle 71 journalled in bearings 72 secured to the bracket 24.

25 The bar 63 is pivotally secured to a detent 73 attached to the bar 22 and when the bar 22 has imparted to it its outward and inward movement, the bar 63 has imparted to it a step by step movement which through the pawl 62 and the ratchet wheel 61 impart a like movement to the sprocket chains 41, 41, carrying the bottle supporting rings.

30 The bar 22 has connected to it a bearing lug 74 which is stationary, a further lug 75, secured to the bar 22 by screw 76 which extends through a slot 77 in the bar 22. 78 is a rod secured at one end in the bearing lug 75. The opposite end of the rod 78 extends slidably through the lug 74 and is provided with a stop pin 79. 80 is a spiral spring which encircles the bar 78. The normal 35 tendency of the spring 80 is to force the bearing lug 75 towards the end of the slot 77 remote from the bearing lug 74. 81 is a guiding plate secured to the bar 22 and is provided with a guiding groove as indicated in dotted lines through which extends a bar 82. The bar 22 is provided with an 40 inclined block 83 with which a detent 84 is designed to engage and ride upon as particularly shown in Fig. 7. 85 is a bracket secured to one end of the bar 22 and through which the end 45 of a rod 86 extends. 87 is a plate secured to the bar 22 above the bracket 85 and is provided at one end with a cam groove 88, one side of which is straight and the other arc-shaped. The cam groove 88 is provided with a spring-pressed controlling pawl 89 which closes one end of the straight side of the cam groove normally. 90 is a block located on the rod 86 and provided with a pin head 91 which extends into the cam groove 50 as clearly shown in Figs. 6 and 7.

60 The rod 86 has an arm 92 secured to it and pivotally connected by a link 93 to a pin 94 on one of the doors. The rod 86 connected to the bar 22 extends rearwardly to the back of the paraffine chamber 32 and has an arm 95 which is 65 connected by a rod 96 to a link 97 and connected to an arm 98 attached to a rod 99 located in bearings 100 on the opposite side of the paraffine chamber 32 to the bearing 101 on the opposite side. The rod 99 has an arm 102 which corresponds to the arm 92 and is connected by a link 103 to a pin 104 on the other door 35. In short, the parts 102, 103, and 104 correspond to the parts 92, 93, and 94, and are designed to act in 70 unison to open and close the doors 35. These 75

latter parts are duplicated at the rear end of the paraffine chamber 32 so that when the paraffine chamber 32 is opened at the front end to let in a bottle, it is likewise opened at the rear end to let out a bottle, and between times the doors are closed to make a completely closed chamber during the paraffining process.

75 The above parts are operated though the bar 22, the rod 86, the block 90, the pin 91 operating in the cam groove 88 as indicated in dotted lines 10 in Fig. 5. The pin 91 passing through the straight portion of the groove to close the doors and the arc-shaped portion to open them as the bar 22 is moved backwards and forwards.

15 The bar 82 shown in Figs. 6 and 7 extends through a slot 34' in one of the side chambers 34 and is bent downwardly inside the chamber where it is connected to a U-shaped bar 105 which carries gate valve 106 opposite the central atomizer 58. The bar 105 has pivotally connected to 20 the top of the same, link 107 which is pivotally connected to the double gate valve 108 by the link 109 which is designed to close the two nozzles 56 located at the side of the paraffining chamber 32. It will, of course, be understood that the link 107 and the link 109, and the gate valve 108 are duplicated to close the nozzle 56 at the opposite side of the paraffine chamber as indicated by dotted lines.

25 The bar 22 at the same time that it is operating with the rod 86 and its co-acting parts so as to open and close the doors at the end of the paraffine chamber, likewise co-acts with the bar 82 to close the nozzles by the gate valves when 30 the doors are open and to open the gate valves when the doors are closed.

35 When the bar 22 moves forward, the lug 75 engages the bar 82 and carries the bar 82 with it through the tension of the spring 80. As the bar 82 is carried forward, it will consequently open the gate valves, and as the forward movement of the bar 22 is continued, the inclined block 83 comes in contact with the detent 84 and raises the bar 82 out of engagement with the lug 75 40 and consequently the spring 80 will extend to its full extent and the gate valves will return to 45 their closed position by their own weight.

50 It will be noticed that the paper bottles are carried in the reversed position in the rings 49 of the carrier chains 41, 41 and in order to place them in their proper position at the filling machine, they must be turned right side up, and to effect this, I have provided in proximity of the discharge end of the carrier chains 41, 41, a 55 dumping chute 110 which is secured to the bracket by metal straps 111 as shown in Figs. 1 and 2. It will be seen in reference to these figures that the chute is at an incline and as the paper bottle passes over the incline of the chute will cause 60 the bottle to fall into an inclined and finally vertical position as shown by the bottles dotted in to the left of Fig. 1.

65 I claim:

1. The combination with a paraffining chamber, 65 and a paraffine source of supply, a central pipe provided with branch pipes leading to each side of the paraffining chamber, atomizer nozzles on the ends of the same, a central atomizer nozzle, a gate valve located opposite each atomizer nozzle, 70 a bar connected to the central gate valve, a bar connected to the side gate valves, a link connecting the aforesaid bars, an operating bar connected to the bar attached to the central gate valve, a detent connected to the operating bar, 75

a bar provided with an inclined block designed to cooperate with the detent and having a lug adjustably mounted thereon, and a lug rigidly mounted thereon, a rod secured at one end in the 5 adjustably mounted and extending freely through the stationary lug and a spiral spring encircling said rod.

2. The combination with a paraffining chamber adapted to receive bottles from a paper bottle 10 making machine, said chamber having end doors slidably mounted so as to move laterally whereby bottles from the bottle making machine may enter and leave, a bar operably connected to the paper bottle making machine, rods supported in 15 suitable bearings on each side of the paraffining chamber, arms secured on the rods and connected by links to the doors on each side, a bracket secured at the end of the main operating rod through which one of the rods extend, a cam 20 plate secured on the main operating bar having a cam groove, a spring held gate, and a block on the rod extending through the bracket and provided with a pin to cooperate with the cam groove whereby the said end doors may be opened and 25 closed.

3. In combination with a paraffining machine having a paraffining chamber and adapted to receive paper bottles from a paper bottle making machine, a paraffine source of supply in said 30 chamber, a supply pipe provided with branch pipes leading to each side of the chamber adapted to impart a film of paraffine to said bottles, atomizer nozzles on the ends of said pipes, a central atomizer nozzle in the bottom of the 35 chamber for spraying paraffine to the interior of the bottles and operating simultaneously with the flow from said branch pipes, a gate valve located opposite each atomizer nozzle, a central gate valve provided with means connecting with 40 said atomizer gate valves, said means comprising a pair of bars, one of said bars being connected to the central gate valve and the other said bar being connected to the side gate valves, a link connecting said bars, an operating bar connected to the bar attached to the central gate 45 valve, and means for shifting the bar adapted to be actuated from said paper bottle making machine.

4. In combination with a paraffining machine 50 having a paraffining chamber adapted to receive bottles from a paper bottle making machine, a paraffine source of supply in said chamber comprising a central supply pipe provided with a plurality of branch pipes extending to either side 55 of the chamber for discharging paraffine to a bottle within said chamber, said branch pipes each having an atomizer nozzle adjacent their discharging ends for distributing the flow of paraffine to the exterior of the bottle, said central 60 discharge pipe in the bottom of the chamber having an atomizer nozzle for distributing the flow of paraffine to the interior of said bottle simultaneously with the flow of paraffine being applied to the exterior of the bottle, each of said 65 atomizer nozzles having a gate valve, the gate valve on the central discharge pipe having means for operating the other said gate valves, and other means connected to said central gate valve adapted to be actuated from said paper bottle 70 making machine whereby the gate valves on said atomizer nozzles open and close simultaneously.

5. In combination with a paraffining machine having a paraffining chamber adapted to receive bottles from a paper bottle making machine, a paraffine source of supply in said chamber comprising a central supply pipe provided with a 5 plurality of branch pipes extending to either side of the chamber for discharging paraffine to a bottle within said chamber, heating means outside of said chamber whereby the paraffine is heated before being discharged, said branch pipes 10 each having an atomizer nozzle adjacent their discharging ends for distributing the flow of paraffine to the exterior of the bottle, said central discharge pipe in the bottom of the chamber having an atomizer nozzle for distributing the 15 flow of paraffine to the interior of said bottle simultaneously with the flow of paraffine being applied to the exterior of the bottle, each of said atomizer nozzles having a gate valve, the gate valve on the central discharge pipe having means 20 for operating the other said gate valves, and other means connected to said central gate valve adapted to be actuated from said paper bottle making machine whereby the gate valves on said atomizer nozzles open and close simultaneously. 25

6. In combination with a paraffining machine having a paraffining chamber adapted to receive bottles from a paper bottle making machine, a paraffine source of supply in said chamber comprising a central supply pipe provided with a 30 plurality of branch pipes extending to either side of the chamber for discharging paraffine to a bottle within said chamber, said branch pipes each having an atomizer nozzle adjacent their discharging ends for distributing the flow of paraffine to the exterior of the bottle, said central discharge pipe in the bottom of the chamber having an atomizer nozzle for distributing the 35 flow of paraffine to the interior of said bottle simultaneously with the flow of paraffine being applied to the exterior of the bottle, each of said atomizer nozzles having a gate valve, a bar connecting said central gate valve and said side gate valves, and other means connected to said central gate valve adapted to be actuated from 40 said paper bottle making machine whereby the gate valves on said atomizer nozzles open and close simultaneously. 45

7. In combination with a paraffining chamber and a paraffine source of supply for imparting 50 a film of paraffine to a bottle within said chamber, a supply pipe provided with a central atomizer nozzle located beneath the mouth of the bottle in the chamber and directed to discharge into said bottle, branch pipes extending in order from 55 the sides of the chamber provided with suitable atomizer nozzles directed toward said bottle, gate valves located opposite the nozzles, and means for throwing said gate valves clear of the nozzles, said means cooperating with other means for 60 delivering the bottle to the chamber to be paraffined, the first said means comprising a pair of arms connecting said gate valves, a link connecting said bars, and an operating bar to one of said other bars whereby the gate valves may 65 be opened simultaneously with the entry of the bottle in the chamber by the said cooperating means whereby the interior and exterior of said bottle is imparted with the film of paraffine. 70
